UNITED STATES PATENT OFFICE.

PHINEAS M. RANDALL, JR., OF WESTERLY, RHODE ISLAND.

PRINTING-PRESS.

No. 819,923.

Specification of Letters Patent.

Patented May 8, 1906.

Application filed October 23, 1905. Serial No. 283,946.

To all whom it may concern:

Be it known that I, PHINEAS M. RANDALL, Jr., a citizen of the United States, residing at Westerly, in the county of Washington and State of Rhode Island, have invented certain new and useful Improvements in Printing-Presses, of which the following is a specification, reference being had therein to the accompanying drawings.

10 This invention relates to printing-machines.

The object of the invention is to so construct a printing-machine, in which at least one member of the printing-couple is a rotating cylinder, that a lost motion may be allowed to one member or a part of one member of the couple under conditions which would otherwise produce blurring or inferiority of impression or work injury to the machine.

15 It is well known that in nearly all kinds of so-called "rotary" printing-presses the printing-couple, consisting of two cylinders or one cylinder and a traveling bed, the cylinders (where two or more are used) or the bed and cylinder constituting the printing-couple are geared so as to have the surface speed of the two members identical.

20 As one of the members has the type or printing-surface and the other member has the impression-surface, it is necessary that the gearing by which the members of the couple are connected shall be calculated with reference to the movement of the peripheries 25 of these surfaces. Usually in addition to a positive gear connecting the members of the couple there are smooth bearing-surfaces on the members of the couple, which bearers come in contact as the parts move forward.

30 As type or plate machines vary in thickness, the elevation of the printing-surface varies from the calculated or theoretical level, and if this variation be in the direction of elevation the face of the form moves faster than it should. If the type is low, the surface moves slower. Under such circumstances there is a tendency of one member of the couple to scrape or strip the surface of the other member. This tendency I overcome 35 in manner I will proceed to describe.

Figure 1 is an end elevation of so much of a two-cylinder or web-printing machine as is necessary to give an understanding of the present invention. Fig. 2 is an end eleva-

tion of the printing-couple, part of the frame being indicated in dotted lines. Fig. 3 is a vertical section of cylinder, showing a yielding impression-shell thereon and showing a reciprocating bed in elevation, parts of the press deemed unnecessary to the invention being omitted. Fig. 4 is an end elevation of part of the couple shown in Fig. 3. Fig. 5 is an elevation of a cam-ring and cams thereon, hereinafter referred to. Fig. 6 is an edge view of cam-ring and cams, showing relation of friction device thereto, as hereinafter explained. Fig. 7 is a diagrammatic broken side elevation of a printing-machine in which a reciprocating bed is one of the members of the printing-couple. Fig. 8 is a cross-section of the same. Fig. 9 is a broken detail section of the traveling bed, its yielding surface, and means for holding the latter by friction. Fig. 10 is a front elevation of a bracket which is attached to the bed and a locking-lever and a friction-holding lever attached thereto. Fig. 11 is an end elevation of cam 42 and the adjustable cam thereon.

In Fig. 1, A represents the impression-cylinder, and B the form-cylinder, of a well-known class of printing-presses. These cylinders are geared to rotate together, as by gears C C, and have bearers D D moving in contact, as usual. The impression-shell of the cylinder A is marked *a* in the drawings and is shown in section in Fig. 8. Now assuming that the type forms or plates *b* are abnormally high then it is apparent that the surface speed of these plates or forms will be greater than the surface speed of the impression-surface of shell *a*, of normal height, and as the cylinders forming the printing-couple are geared to move together there must be a scraping or blurring movement of the surfaces. Such movement may be very small, but is often great enough to give a blurred appearance to the printed sheet. Moreover, the strain and wear on a press under such conditions are very great. I overcome the defects by permitting a yielding movement of the impression-surface of shell *a* in the instance cited, as I will explain; but it is obvious that the yielding might as well be on the part of the other member of the couple—that is, of the forms or plates on the form-cylinder.

The impression-shell *a* may be divided on a radial line or lines, as *c*, Fig. 3, or it may be a hollow cylinder having a normal initial posi-

tion, in which it is held by strong springs 1, 1, carried on the ends of the cylinder and rigidly secured to a hub on the cylinder, as at 2, 2. Pins 3, 3, projecting from the end of the cylinder, define the initial position of these springs.

Pins 4, 4 extend from the impression-shell *a* through curved slots in the end of the cylinder in position to bear against the springs 1. Then the abnormal movement of the plates 10 or forms *b* will simply produce a corresponding movement of the impression-surface of shell *a* against the resistance of springs 1. The gears and bearers will move in unison, and the form-surface and impression-surface 15 will also move in unison, but at a different velocity from that of the bearer movement, and there will be no unusual strain on the gears.

When the drag of the forms on the impression-surface has ceased by the rotation of the cylinder to a break in the forms, (as between sheets or between pages,) the springs 1 will restore the surface shell *a* to normal position, so that the leading edges of the printing-couple are in register. To prevent a too rapid recoil of the springs 1, a friction-holding device may be applied. Thus let 6 indicate a bracket at the end of the cylinder A, and 7 a crank-lever pivoted in the bracket. A roller 30 8 is journaled on the outer arm of lever 7. (See Figs. 1, 5, and 6.) A pin 9 extends through the end flange of cylinder A, and its inner end rests against the end of impression-shell *a*. Attached to the frame of the press 35 there is a cam-ring 12, on which cam-pieces 13 are adjustable, being held in place by set-screws 14 or in other suitable manner. (See Fig. 6.) As the cylinder rotates the lever or levers 7, carried thereby, will pass the cam-rings 13 on the fixed ring 12, and roller 8, engaging said cams, will rock lever 7, thus pressing in the pin 9 to apply a strong holding-pressure against the end of impression-shell *a*. The circumferential length of cam 13 will determine how long this pressure shall be maintained. The cams will ordinarily be placed 45 opposite the breaks in the forms and are adjustable and removable, so that the press may be adjusted to different type or plate forms. As soon as roll 8 has passed off from cam 13 the springs 1 will resume control of the impression-piece.

When the invention is applied to a cylinder having grippers to grasp a sheet, it is important that the yielding part be held at the instant the grippers close to prevent the grippers from moving the yielding piece. To this end a pin 20 is passed through the end disk of the cylinder A, and this pin is normally held 55 out by forked spring 21, embracing the head of pin 20. A fixed cam 22 on the frame encounters the head of pin 20 as the cylinder rotates and forces the point of the pin into a hole 23 in shell *a*, while the cylinder moves 60 out the pin past the cam 22, after which the

spring 21 will withdraw pin 20, and the shell *a* again comes under the control of springs 1. Precisely the same principles are applicable to a printing-press in which one of the members of the printing-couple is a reciprocating 70 bed instead of a rotating cylinder.

A printing-cylinder is substantially the same as a curved bed or a flat bed is the surface of a cylinder straightened out. Cams on the side of the frame will operate in the 75 same way to move locking pins or levers outward or inward, as on a frame past which a cylinder rotates.

In the modification Figs. 7 and 8 the flat bed 30 of the press has longitudinal recesses 80 31. In the bottom of each recess 31 there is a hardened plate 32, which plates are just the length of the yielding bed 33, on which the type-forms rest. Rollers 34 rest on the hardened plates 32, and a hardened track-plate 85 35 runs on these rolls. The bed 33, being rigid with the track-plates, may move lengthwise of bed 30 with very little friction and the hardened plates prevent rapid wear of the parts. At each end of the bed 33 there are 90 springs 36, attached to the lower bed 30, and extending up through holes in this lower bed and resting against the ends of bed 33 to hold said bed normally in position to move with bed 30, but permitting said bed 33 to have an 95 independent movement against the pressure of the springs, when the conditions of surface contact between the forms on bed 33 and the impression-cylinder call for a redisposition of the surfaces of the printing-couple. The bed 100 30 has brackets 40 secured to its sides, and a lever 41 is pivoted in each bracket 40. These levers of course participate in the longitudinal movement of the press-bed. Cams 42 on the frame at the sides of the press-bed are engaged by levers 41 as the bed reciprocates and the levers 41 are turned on their pivots against the pressure of springs 43 by engagement with these cams as the levers move past the cams. Brackets 40 carry also levers 45, 105 which operate in the same way as do levers 41 to press the pins 46 and so apply friction to the bed 33 and resist its yielding. Levers 41 press in pins 47 to lock the bed 33 positively except when unlocked by the action of 110 the cams 48, which cams are adjustable, as has already been described with reference to 115 cams 14.

From the foregoing it should be understood that the operation of the press is substantially the same whether the printing-couple be two cylinders or a bed and a cylinder. In either case one member of the couple has a yielding part which bears one of the contact-surfaces, and this yielding part is held to 120 normal position by springs and may be locked in such position. The movement of the member which bears this yielding part unlocks the same at a predetermined place, determined by the adjustment of a cam on the 125 130

frame, and friction may be applied to the yielding part to render its resistance less easy or to check either its movement or its recoil.

It will be apparent that the mechanism is capable of very material modifications, but the principle of operation is the same—namely, that one of the contact-surfaces is permitted to yield in the direction of its travel in order to compensate for departures from the theoretical level of contact and prevent wear not only on the printing and impression surfaces, but on the gears by which the members of the couple are compelled to travel together.

15 The advantages of my invention are great. Absolute register of the members of the printing-couple may be had, even though the forms are high or low, and this without strain on the gears or bearers of the press. Much better printing may be done where the types or forms are imperfect than has heretofore been the case.

I claim—

1. In a printing-machine, the printing-couple geared to move at uniform speed, with a contact-piece of one of the couple held by springs so as to yield in the direction of movement under increased pressure.

2. The combination with the cylinder of a printing-press, of an impression-shell, and springs to hold the same to operative position, while permitting a circumferential yielding.

3. The combination with the printing-couple of a printing-machine, of a yielding contact-piece attached to one of the members and means to control the yielding thereof, means for positively locking such yielding piece, and means for unlocking it at a predetermined position in its movement.

4. The combination with the printing-cou-

ple of a printing-machine, of a yielding part bearing a contact-face, means for locking this part, and means for unlocking it as the member moves.

5. The combination with a cylinder of a printing-press, of a rotatively-yielding shell, springs for holding the shell in normal position, and means for locking the shell to the cylinder.

6. The combination with the cylinder of a printing-press, of a rotatively-yielding shell, means for locking the shell to the cylinder, and means for unlocking the shell by the movement of the cylinder.

7. The combination with the cylinder of a printing-press, of a rotatively-yielding shell, a friction device for obstructing the yielding of said shell, and means for applying the friction device.

8. The combination with the cylinder of a printing-press, of a rotatively-yielding shell, a frictional holding device for said shell, and adjustable cams on the frame by which the pressure of said holding device is applied.

9. The combination with the cylinder of a printing-press, of a rotatively-yielding shell, a locking-pin in position to enter said shell, a cam to lock said pin, and means for withdrawing said pin.

10. The combination with one of the members of a printing-couple, of a yielding part bearing one of the contact-surfaces, a lock by which said piece is held against yielding, and means for automatically unlocking said piece to permit the yield.

In testimony whereof I affix my signature in presence of two witnesses.
